UNITED STATES PATENT OFFICE

138,541

DESIGN FOR A RECEPTACLE FOR DOMESTIC GAS SYSTEMS

Charles E. Lenihan, Kansas City, Mo., assignor to
Butler Manufacturing Company, Kansas City,
Mo., a corporation of Missouri

Application November 6, 1943, Serial No. 111,610

Term of patent 14 years

(Cl. D52—2)

To all whom it may concern:

Be it known that I, Charles E. Lenihan, a citizen of the United States, residing at Kansas City, in the county of Jackson and State of Missouri, have invented a new, original, and ornamental Design for a Receptacle for Domestic Gas Systems, of which the following is a specification, reference being had to the accompanying drawing, forming part thereof, in which

Fig. 1 is a side elevational view of a receptacle for domestic gas systems showing my new design; and

Fig. 2 is a front view showing the door that opens into the base or instrument house.

The side view of the receptacle not shown in full is a mirror image of the side elevational view shown in Fig. 1. The back of the receptacle is identical with the front view shown in Fig. 2, except that the two gauges appearing directly above the lower handle are omitted.

I claim:

The ornamental design for a receptacle for domestic gas systems, substantially as shown and described.

CHARLES E. LENIHAN.
